UNITED STATES PATENT OFFICE.

GEORGE L. RAWDON, OF LAKEWOOD, OHIO.

TELEGRAPH RELAY.

Application filed November 10, 1923. Serial No. 673,912.

To all whom it may concern:

Be it known that I, GEORGE L. RAWDON, a citizen of the United States, and resident of Lakewood, in the county of Cuyahoga and State of Ohio, have invented certain new and useful Improvements in Telegraph Relays, of which I hereby declare the following to be a full, clear, and exact description, such as will enable others skilled in the art 10 to which it appertains to make and use the same.

The objects of the invention are to provide means for simplifying the construction of a relay, containing main and holding 15 magnets, and particularly relates to a modified form of construction of the pole pieces of the holding magnet permitting them to come into close proximity to the armature lever without materially changing the 20 weight of the armature and without increasing its length or greatly modifying its shape.

To accomplish this result the holding-magnet is placed on one of its longitudinal edges by the side of the main magnet, and 25 the pole pieces are extended laterally around one of the sides of the main magnet in such a manner that they are opposed to each other, and to the armature lever at a point central of said lever, so as to become efficient in action.

In this manner the structure of the relay remains unchanged and the entire arrangement and assembly of the various parts is convenient and compact in shape.

30 The invention is hereinafter more fully described, illustrated in the accompanying drawings, and specifically pointed out in the claims.

In the accompanying drawings Fig. 1 is 35 a transverse section of the device on line 1—1, of Fig. 2, Fig. 2 is a plan thereof, Fig. 3 is a side elevation thereof, Fig. 4 is a perspective of the armature lever.

In these views 1 is the base on which the 40 parts are assembled. 2 is the main electro-magnet. 3 is the holding electro-magnet which is placed vertically on edge closely adjacent to one edge of the main magnet thus making a compact structure. 4 is the 45 soft iron armature lever of the ordinary length which vibrates against the tension of a spring 5 between the front and rear electrical contacts 6 and 7 respectively. 8, 8 are the pole pieces of the main magnet which 50 55 when the main electric current energizes the main magnet attract the lateral wings or

side pieces 9 extending laterally from each side of the armature.

10, 10 are pivotal supports for the armature, positioned upon standards 11, 11 on 60 the base. 12, 12 are the pole pieces of the holding magnet which are laterally extended so as to encircle one side of the main magnet and are near together at the axial center of the main magnet so as to attract the 65 armature when the local electric current is passed through the holding magnet. 13, 14 are posts through which the threaded supporting rods for the magnets are respectively passed, and in which they may be independently adjusted by means of nuts 15, 15, and 16 to regulate the gaps between their 70 respective poles, and the armature. The front and rear contacts 6 and 7 are screw threaded and adjustable by means of nuts 75 6', 6', and 7', 7' in posts 17 and 18.

In operation when the main current is passed through the main magnet thereby energizing the same, the armature lever will be drawn against the tension of the springs 80 to contact with its front contact point 6. Also if an electric current is caused to flow through the holding magnet and afterwards the electric current is broken or cut off from the main magnet, the armature lever will 85 remain on the front contact 6, or in the same position, by the effect of the holding magnet. Vice versa, if an electric current is caused to flow through the holding magnet thereby magnetizing the same the armature 90 lever will be drawn to its front contact and if an electric current is caused to flow through the main magnet, and the current is afterwards broken or cut out from the holding magnet the armature lever will 95 remain upon the front contact, or in the same position by the attraction of the main magnet.

Having described the invention what I claim as new and desire to secure by Letters Patent is:

1. In a relay, the combination with a main electro-magnet and pole pieces, and a holding electro-magnet of a support therefor, a vibratable armature lever common to both magnets, and pivotal support therefor at one end thereof, and front and rear contact points therefor, and laterally extending pole pieces for said holding magnet the free extremities, said pole pieces being opposed to said common armature lever, said main electro-magnet being positioned horizontal- 105 110

ly on said base, and said holding electro-magnet being supported upon one longitudinal edge adjacent one side of said main electro-magnet, the pole pieces of said holding electro-magnet encircling said adjacent side of said main electro-magnet.

2. In a relay, the combination with a main electro-magnet and pole pieces and a holding electro-magnet of a support therefor, a vibratable armature lever common to both magnets and pivotal support therefor at one end thereof, and front and rear contact points therefor, and laterally extending pole pieces for said holding magnet, the free extremities of said pole pieces being opposed to said common armature lever, said

main electro-magnet being positioned horizontally on said base and said holding electro-magnet being supported upon one longitudinal edge adjacent to with one side of said main electro-magnet, the pole pieces of said holding electro-magnet encircling said adjacent side of said main electro-magnet, said armature being provided with lateral extensions opposed to the poles of said main electro-magnet, the central portion thereof being opposed to the poles of said holding electro-magnet.

In testimony whereof, I hereunto set my hand this 1st day of November 1923.

GEORGE L. RAWDON.
